UNITED STATES PATENT OFFICE.

CHARLES E. SCRIBNER, OF JERICHO, VERMONT, ASSIGNEE TO WESTERN ELECTRIC COMPANY, OF NEW YORK, N. Y., A CORPORATION OF ILLINOIS.

TELEGRAPH-RECEIVER.

1,107,366.

Specification of Letters Patent. Patented Aug. 18, 1914.

Application filed November 26, 1911. Serial No. 662,844.

To all whom it may concern:

Be it known that I, CHARLES E. SCRIBNER, citizen of the United States, residing at Jericho, in the county of Chittenden and State of Vermont, have invented a certain new and useful Improvement in Telegraph-
5 Receivers, of which the following is a full, clear, concise, and exact description.

This invention relates to selecting systems particularly adapted for use in printing telegraph receivers, and has for one of its objects to provide an improved system whereby high speed, accurate operation and a simplification of the controlling apparatus
10 are obtained.

Another object is to provide an improved selecting apparatus comprising, among other things, a novel arrangement of electromagnetic structures, whereby any one of a number
20 of elements may be chosen at will.

A further object is to provide a controlling system in which the arrangement of circuits and apparatus is such that a combination of impulses from a sending station sets
25 up or establishes such electrical changes in said circuits and apparatus that after the cessation of the combination of impulses the circuits and apparatus will complete their proper sequence of operations, and while so
30 doing another combination of impulses may be arriving from the sending station to initiate another similar sequence of operations. This feature of the invention is, for convenience, called the "overlapping cycle"
35 system of operation, and is one that renders the system capable of rapid operation and in which it is practically impossible for the various combinations of impulses to follow each other so fast as to disarrange the system.
40

The above and other objects of the invention will be fully set forth in the following description and claims, and will be more readily understood by reference to the accompanying drawings.

In the drawings Figures 1 and 2 combined constitute a diagram illustrating a complete receiving system embodying the invention, Fig. 2 showing, in detail perspective, so much of the mechanical features as are necessary to illustrate the results which may be accomplished.

In Fig. 1 is shown two groups of relays, one group, comprising relays 101, 102, 103 and 104, being connected to main line con-

ductor L¹, and the other group, comprising relays 105, 106, 107 and 108, being connected to main line conductor L², both groups being connected to ground through conductor 109. Of the group connected to line conductor L¹ 60 relays 101, 102 and 103 are polarized and respond,—relays 101 and 102 to negative current over L¹ alone or over L¹ and L² simultaneously, and relay 103 to positive current over L¹. Relay 104 is neutral and responds to positive or negative current. Of the group connected to line conductor L², relays 105, 106 and 107 are polarized and respond,—relays 105 and 107 to positive current over L² alone or over L¹ and L² simultaneously, and relay 106 to negative current over L². Relay 108 is neutral and responds to positive or negative current.
65

Switching levers 110, 111, 112, 113, 114 and 115 are provided, and are normally in contact with conductors 126, 127, 128, 129, 130 and 131 respectively. These levers are operated simultaneously by the switching relay 116 and move from their normal position to their alternate position in contact with the conductors 160, 161, 162, 163, 164 and 165 and therefore form an electro-magnetically operated transfer switch. Switch lever 110 is connected to the armature of relay 107 by conductor 120; switch lever 111 to the front contact of relay 105 by conductor 123; which lever 112 to the armature of relay 103 by conductor 117; switch lever 113 to the armature of relay 102 by conductor 119; switch lever 114 to the front contact of relay 101 by the conductor 125; and switch lever 115 to the armature of relay 106 by the conductor 122.
70

Group relays 132, 133, 134, 135, 136 and 137 are provided, connected respectively to the conductors 126, 127, 128, 129, 131 and 130. These relays are energized by current from sources 138, 139, 140, 141, 142 and 143, as shown. They have two armatures, and when their energizing circuit is closed by 100 the proper combination of relays 101 to 108 inclusive close for themselves a locking circuit from their energizing source, through their windings, bottom armature, conductor 144, switching relay 116, conductor 146, 105 armature of auxiliary restoring relay 147, resistance 148 to ground. Relay 137, which has been described as a group relay, is used for a special purpose and does not require a locking circuit. Relays 132, 133, 134 and 110

135 close, at their top armature, an energizing circuit for the circuit-holding relays 151, 152, 153 and 154, respectively.

Type or character selecting magnets 11 to 16 inclusive, 21 to 26 inclusive, 31 to 36 inclusive, and 51 to 56 inclusive are grouped about a shaft 216, which carries a type wheel 221 as shown at the right of Fig. 2. Each magnet has two fixed energizing windings and an armature lever 213. The magnetic structure of these type selecting magnets is marginal, that is, more than one winding must be energized in order to cause the attraction of lever 213. The windings are therefore cumulative in their magnetic effect. As shown diagrammatically in Fig. 2, they are arranged in two series of groups, with the upper windings of one group as 24, 26, 22, 21, 25 and 23 in series in the conductor 205, this conductor 205 leading to the conductor 156 connected with the energizing winding of the circuit-holding relay 154. The lower coils of these type magnets are also arranged in a series of groups, the windings of any group, as 21, 11, 51 and 31, being arranged in series and connected to a conductor 162 leading to the alternate contact of the switch lever 112. A shift relay 43, a back shift relay 44, a reset and paper-shift relay 41, and a reset relay 42 are also provided. The relays 41, 42 and 43 are each provided with three windings, two of which are energizing windings, the third being a locking winding. Relays 41, 42 and 43 are so proportioned that the energizing circuit must pass through two of the windings in series in order to energize the magnets which, when they attract their armatures, close a locking circuit for themselves through the locking winding. The back shift relay 44 is provided simply with two energizing windings.

The first impulse of a combination of impulses arriving over the line wires L^1 and L^2 selectively energizes one of the group relays 132 to 135 inclusive, closing thereby a section of the type magnet selecting circuit and also at the cessation of the impulse energizing the switching relay 116, moving the switching levers 110 to 115 inclusive into position preparatory to receiving the second impulse of the combination and thereby closing a second section in the type magnet selecting circuit. The second impulse arriving over the line wires L^1 and L^2 completes the circuit through the selected type magnet thereby moving its armature into position and initiating the printing operation. The printing operation, and the operations of spacing and resetting the paper carriage, shifting the type wheel, paragraphing and paper lifting will be described in connection with the detailed description of these circuits.

Let it be assumed that the operator at the

transmitting or distant station desires to print on the recording sheet of the mechanical printer, shown in Fig. 2, certain desired characters. Let it be specifically assumed that she desires to print the word "to" followed by a space and then another word. To accomplish this, she first depresses the key marked "T", then the key marked "O", then the space key, and so on. Let it be assumed that the combination of impulses necessary to print the letter "T" is composed of two impulses, the first, a negative impulse over line L^1 , the second, a positive impulse over line L^2 , these two impulses being separated by a brief interval of no current; that the combination of impulses necessary to cause the printing of the letter "O" is composed of two impulses, the first, a positive impulse over L^1 and L^2 simultaneously, the second, another negative impulse over L^1 , the two impulses being separated by a brief interval of no current, as before; the word space, by a single negative impulse over L^1 and L^2 simultaneously. When the negative impulse arrives over line L^1 it passes through all the relays 101, 102, 103 and 104 to conductor 109 to ground. The polarized relays 101 and 102 and the neutral relay 104 are energized, attracting their armatures. The attraction of the armatures of relays 101 and 104 is without effect. Armature of relay 102, however, closes a circuit which may be traced from ground, armature of relay 108, conductor 118, armature of relay 102, conductor 119, switch lever 113, conductor 129, group relay 135, battery 141, to ground. Closure of this circuit energizes relay 135, which attracts both its armatures, and closes a locking circuit for itself through battery 141, its energizing winding, bottom armature, conductor 144, switching relay 116, conductor 146, armature auxiliary restoring relay 147, resistance 148, to ground. The switching relay 116, however, will not be energized until the deenergization of the negatively polarized relay 102, since so long as such relay is energized a shunt to ground exists around the winding of the switching relay.

Upon the cessation of current over the line conductor L^1 , due to the ending of the first impulse, the negatively polarized relays 101 and 102 and the neutral relay 104 are deenergized, relay 102 opening the shunt around the switching relay 116. This switching relay will therefore be energized in series with the group relay 135, maintaining such relay energized, and the switching relay will cause the movement of all the switching levers 110, 111, 112, 113, 114, 115 from their normal positions (in contact with the conductors 126, 127, 128, 129, 130 and 131, respectively) to their alternate positions in contact with the conductors 160, 161, 162, 163, 164 and 165, respectively. The

interval of no current having terminated, the second controlling impulse is initiated and is positive battery impressed upon the line conductor L^2 . This impulse will energize the positively polarized relays 105 and 107 and the neutral relay 108 passing through the conductor 109 to ground. Relays 105, 107 and 108 attract their armatures, but the attraction of the armature of relay 105 and the armature of neutral relay 108 is without effect. Armature of relay 107, however, established a circuit which may be traced as follows:—From battery 201, armature and back contact of the selector relay 202, the printing relay 203, conductor 204, the conductor 205, including the top windings of the type magnets 24, 26, 22, 21, 25 and 23 in series in the order named, conductor 156, through the winding of the circuit-holding relay 154, upper armature of the group relay 135, conductor 150, winding of the restoring relay 171, the conductor 200, middle winding of the shift relay 43, lower winding of the type magnets 23, 13, 53 and 33 in series, in the order named, conductor 160, armature 110, conductor 120, armature and front contact of the positively polarized relay 107, conductor 121, armature and back contact of neutral relay 104, to ground. The type magnets 24, 26, 22, 21, 25, 13, 53 and 33, through one winding of each of which the circuit just traced passed, will not be energized since the battery 201 supplying current to the circuit traced and the individual windings of the various type magnets are so proportioned that current in the series circuit traced when passing through a single winding alone of any one of the type magnets shown will be insufficient to energize such type magnet and it will be only when current through such series circuit passes through both of the windings of any one of the type magnets (magnet 23 in the circuit just traced) that such type magnet will be energized. However, when such type magnet has once attracted its armature due to energization by current through both of its windings, current through its upper winding alone will be sufficient to maintain such type magnet energized to keep its armature in attracted position. This is for a purpose which will be presently described. Closure of the series circuit traced above also energizes the printing relay 203 which attracts its armature completing a circuit from battery 201, armature and back contact of the selector relay 202, spacing magnet 209, printing magnet 210, stop magnet 211, armature and front contact of printing relay 203, resistance 212, to ground, thereby energizing the spacing, printing and stop magnets for a purpose to be hereinafter described.

The energization of the restoring relay 171, due to the closure of the series circuit

traced, has caused the attraction of its armature. The energization of the circuit-holding relay 154 has established for itself a locking circuit through its winding, front contact and armature, through resistance 170 to ground, which circuit acts as a shunt of that part of the series circuit traced containing the restoring relay, the middle winding of the shift relay 43, the lower windings of the type magnets 23, 13, 53 and 33, the conductor 160, switching lever 110, conductor 120, armature and front contact of the positively polarized relay 107, conductor 121, armature and back contact of the neutral relay 104. The energization of restoring relay 171 caused it to attract its armature thus energizing auxiliary restoring relay 147 from battery 141, and breaking circuit through resistance 148. When the shunt circuit for the restoring relay 171, above traced, is established the energizing current which was flowing therethrough will be diverted to ground through the resistance 170 to such an extent that said restoring relay will be deenergized, thereby opening the circuit heretofore traced through the group relay 135 and the switching relay 116, so that such group relay 135 and the switching relay 116 will be restored to normal.

The type magnet 23, which was energized by the series circuit above traced, will not be affected by the deenergization of the restoring relay 171 and the group relay 135, but will be maintained energized since its upper winding is in series with the winding of the circuit-holding relay 154 and the printing relay 203 until the printing operation has taken place. This circuit will be maintained independent of the energized or deenergized condition of the positively polarized relay 107, which closed the original energizing circuit of the type magnet 23, and this relay 107, may, after its brief period of energization, return to its normal condition, without affecting the printing operation which follows.

It will be evident from an inspection of the drawings that immediately upon the energization of the circuit-holding relay 154, the apparatus is in condition to receive the first impulse of the combination of impulses for the next character selected at the sending station—in the case assumed, the letter "O"—and this impulse may be received and the proper group relay energized while the printing operation for the character "T" is still uncompleted, without in any way affecting such operation. The first impulse for the next character—"O"—is positive battery impressed upon both line conductors L^1 and L^2 simultaneously. In response to this impulse, relays 103, 104, 105, 107 and 108 will be energized, and the circuit for the group relay responsive to this

impulse may be traced from the battery 139, group relay 133, conductor 127, switching lever 111, conductor 123, armature of relay 105, conductor 124, armature of relay 104, to ground. The energization of this group relay 133 will, in a manner analogous to that described for the group relay 135, close by the attraction of its armatures, a locking circuit for itself to maintain it energized after the cessation of the controlling impulse, and 5 prepare a circuit through its upper armature for the circuit-holding relay 152. It will be apparent, however, that the energization of the group relay 133 and the attraction of its armatures can in no way affect the circuit already established and maintained by the 10 circuit-holding relay 154. The cycle of operations of successive printing operations may overlap therefore, to the extent that the 15 first impulse of the combination of impulses of a succeeding character may be transmitted to the receiving station before the termination of the printing operation produced by the combination of impulses of the 20 preceding character.

The printing operations which are initiated and follow immediately after the closure of the energizing circuits for the circuit-holding relay 154, the type magnet 23, 25 the spacing magnet 209, the printing magnet 210 and the stop magnet 211 are produced in the following manner:—Immediately upon the energization of the type magnet 23 it attracts its armature 213, drawing up the inner end thereof, which projects toward the center of the circle of type magnets, so that it comes into the path of the revolving arm 215 attached to the type shaft 216. At the same time the stop magnet 211 30 attracts its armature 217, withdrawing the stop arm 218 from engagement with the teeth of the wheel 220, also attached to the type shaft 216. The type shaft 216 has fixed thereon the type wheel 221, upon which 35 are two rows of type, the upper row thereon being the type by which the printing is ordinarily effected and the lower row being the type from which printing is effected when the type wheel is in its shifted position. The type shaft 216 rotates in a counter-clockwise direction, when viewed from 40 above. This shaft is rotated in the direction specified by the motor 222, connected to any suitable source of power.

45 The characters on the type wheel 221, fastened to the shaft 216, are so arranged upon such type wheel that when the arm 215 comes in contact with the raised end of the armature of any energized type magnet, the 50 type wheel will at that time be in position to print one of the two characters with which that particular type magnet is associated. Therefore, in the character selected, the armature 213 of the type magnet 23 having 55 been moved to such position that the end

thereof will rest in the path of the arm 215, when such arm 215 comes in contact with the armature 213, they stop the rotary movement of the type shaft and the type wheel is brought to rest in position to print the character "T." As soon as the arm 215 is brought to rest by the armature 213 of the printing magnet, a circuit is established from ground, armature 213, arm 215, selector relay 202, battery 201. The closure of 70 this circuit causes the energization of the selector relay thereby opening the circuits for and deenergizing the stop magnet, printing magnet, spacing magnet, type magnet 23 and the circuit-holding relay 154. The 75 printing magnet is immediately deenergized and by the back stroke of its armature causes the printing of the character "T" upon the paper.

The printing operation initiated and controlled by the first combination of impulses sent from the transmitting station and the circuits controlled from such station are now open unless the controlling impulses for a subsequent character have been initiated. 80 The deenergization of the circuit-holding relay 154 allows its armature to retract, opening its locking circuit and preventing any reclosure of the circuit for the type magnet except in response to proper impulses received over the line conductors L¹ L² from the transmitting station. The further operations of the printing mechanism which relate specifically to the operations of the stop magnet and the retractor magnet are 85 90 95 100 purely automatic and will now be described.

Immediately upon the energization of the selector relay 202 the printing operation took place. The selector relay, however, closed at its front contact a circuit for the 105 retractor magnet 223. By reference to Fig. 2 it will be seen that in the normal position of the apparatus with both the stop magnet 211 and the retractor magnet 223 deenergized, the type shaft 216 is held 110 against rotation by the engagement of the projection 218, on the armature 217 of the stop magnet 241 with a tooth of the wheel 220 fastened to the type shaft. During the printing operation the type shaft is held in 115 the proper position by the engagement of the arm 215 with the armature 213 of the energized type magnet. At this time, however, the stop magnet is deenergized and the retractor magnet is energized. The deenergization of the stop magnet is without immediate effect. The energization of the retractor magnet, however, by the engagement of the projection 225 on its armature 224 with one of the teeth of the wheel 220 upon 120 125 130 the type shaft causes a slight counter movement, this movement being in a clockwise direction of the type shaft, such movement being sufficient to remove the arm 215 from engagement with the armature 213 but not

sufficient to allow the projection 218 on the armature of the stop magnet to engage with the stop surface of the tooth upon the inclined surface of which such projection now rests. The arm 215 having been withdrawn from contact with the armature 213 by the energization of the retractor magnet the circuit for the selector magnet 202 is opened allowing its armature to retract, causing the deenergization of the retractor magnet. The retractor magnet thereupon permits its armature to withdraw the projection 225 from engagement with the tooth on the wheel 220, and the type shaft rotates in its normal direction for not quite the length of one tooth on the wheel 220 or until stopped by the engagement of the projection 218 on the armature 217 of the stop magnet with the stop surface of the next tooth on said wheel. In this movement the type shaft has moved a distance such that if the succeeding character should chance to be the same as the one just printed, the type shaft will make almost a complete revolution before being stopped by the armature of the energized type magnet; that is, the type shaft will rotate before being stopped by the projection on the armature of the stop magnet sufficiently far for the arm 215 to pass beyond the type magnet armature 213 by which it has just previously been stopped. This operation is for the purpose of insuring the proper inking of the type wheel when printing successively the same character. If now, no subsequent printing operation has been initiated, the entire apparatus with the exception of the paper carriage and the type wheel proper returns to normal. Obviously, the paper carriage is not restored to normal but moves step by step to print the successive characters, in the proper order; that is, in succession across the record medium or paper. The type wheel also remains in the position in which it has been left, ready for the next succeeding operation when it will move to the desired position and again rest, and so on.

It will be recalled that in the description of the operation of the system the first controlling impulse of the letter "O" followed the last controlling impulse of the letter "T" before the printing operation for the letter "T" had been completed, and without in any way affecting such printing operation. This impulse was positive battery impressed simultaneously on the line conductors L^1 and L^2 , and in response thereto the group relay 133 was energized and locked up. As in the case of the letter "T" a certain period of time elapses between the cessation of the first impulse of the combination of impulses and the initiation of the second impulse of such combination, during which period the armatures of the energized receiving relays return to normal

breaking the shunt around the switching relay 116, which is thus energized moving the switching levers 110 to 116 inclusive from their normal to their alternate contacts. The second controlling impulse for the letter "O" is—in the case assumed—negative battery impressed upon the line conductor L^1 , and in response thereto, receiving relays 101, 102 and 104 are energized, establishing circuits similar to the circuits hereinbefore described; the one through the type magnet being through battery 201, armature and contact of the selector relay 202, printing relay 203, conductor 204, conductor 207, in series through the upper winding of type magnets 54, 56, 52, 51, 55 and 53, through conductor 158, circuit-holding relay 152, contact and upper armature of group relay 133, conductor 150, restoring relay 171, conductor 200, middle winding of reset relay 42, the lower winding of type magnets 22, 12, 52, 32 in series, conductor 163, switching lever 113, conductor 119, armature and contact of negatively polarized relay 102, conductor 118, armature and back contact of neutral relay 108, to ground; the circuit through the spacing, printing and stop magnets being identically as before. The circuit through the circuit-holding relay 152 closes a locking circuit for such relay 95 through its contact and armature, resistance 170 to ground, as in the case of the circuit-holding relay 154. From this point on the operation of the system and apparatus is precisely analogous to the operation hereinbefore described with reference to the printing of the letter "T". In this case, however, the type magnet 52 is the one energized and which will be maintained energized by the circuit-holding relay 152 and therefore in the succeeding printing operation it will be the character "O" that is printed.

The printing of the other characters under the control of the type magnets can be controlled in the manner described. In each case the first impulse will select and lock up a group relay, thereby selecting a vertical group of type magnets, and the second impulse will select an intersecting horizontal group of type magnets and initiate the printing operation.

When it is desired to print a character upon the lower row of type of the type wheel 221, it is necessary before sending the character selecting combination of impulses to send such a combination of impulses as will operate the shift magnet 226, which will attract its armature 227 sliding the type wheel 221 upwardly through the medium of the roller 228 carried at the outer end of the armature 227 bringing the lower row of characters into operative position. Let it be assumed that a combination of impulses composed of a negative impulse over

line conductor L^2 followed by a positive impulse over line conductor L^1 , the two impulses being separated by the usual interval of no current, will initiate the operation 5 of the shifting magnet 226. The selection and energization of the shift relay 43 is effected in a manner precisely analogous to the selection and energization of a type magnet as hereinbefore described. In this 10 case, however, the energizing circuit is somewhat different from the energizing circuit hereinbefore traced for a type magnet in that it does not include a circuit-holding relay, nor is a circuit closed through the 15 spacing, printing and stop magnets. The circuit established as a result of the combination of impulses arriving at the receiving station may be traced from battery 229, top winding of back shift relay 44, resistance 230, through the top windings of reset relay 42, reset and paper shift relay 41, shift relay 43, in series, conductor 155, front contact and top armature of group relay 136, conductor 150, restoring relay 171, conductor 200, middle winding of shift relay 43, in series, through the bottom winding of type magnets 23, 13, 53 and 33, conductor 160, switching lever 110, conductor 120, front contact and armature of positively polarized relay 107, conductor 121, back contact and armature of neutral relay 104, to ground. This circuit will remain closed only so long as the second controlling impulse from the sending station continues. 35 Closure of this circuit energizes the shift relay 43 which attracts its armature and completes a locking circuit for itself, which may be traced from battery 231, shift magnet 226, conductor 232, lower winding and armature of shift relay 43, conductor 233, contact and armature of back shift relay 44, conductor 234, armature and contact of special relay 235, to ground. Closure of this circuit energizes shift magnet 226 which 40 attracts its armature forcing roller 228 on the outer end thereof against type wheel 221 and lifting it upward so that when succeeding printing operations take place the alternate characters on the lower portion of 45 the type wheel will be the ones used. This circuit through the shift magnet 226 will be maintained until the back shift relay 44 is energized, thus breaking the locking circuit for the shift relay or until the record 50 carriage 270 is reset, as will hereinafter be described.

After the selection and energization of the shift relay 43 all of the controlling circuits are without delay returned to their normal 60 condition since there is, in this case, no means for maintaining the series circuit after the termination of the second controlling impulse. As soon as this circuit is opened the restoring relay 171 will open the 65 circuit for the switching relay 116 and the

group relay 136 and the apparatus is ready for another controlling operation.

The selecting operation of the back shift relay 44 will be readily understood from the operations already described. When this relay has been selected in the manner described for the type magnets and shift relay, it opens the circuit at its armature and front contact, through the shift magnet and the bottom winding of the shift relay. Deenergization of the shift magnet allows its armature to retract and type wheel 221 returns to its lower or normal position so that until the shift relay is again energized only the upper row of type will be used.

The forward movement of the record carriage 270 is controlled by the spacing magnet 209. It will be recalled that simultaneously with the energization of a selected type magnet a circuit was established 70 through the spacing, printing and stop magnets. The spacing magnet on its energization attracts its armature 237 rotating the shaft 238 through the space of one tooth of the pinion 239 by means of the pawl 240. A pinion 241 on the end of shaft 238 meshes with a rack 242 on the carriage 270 so that on the rotation of the shaft 238, as above described, the carriage will be stepped forward 75 through the space of one letter. When the spacing, printing and stop magnets are deenergized the printing operation is completed by the armature of the printing magnet which operates on its back stroke to print the character selected by the type magnet. 80

When it is desired to leave a space between successive words, a special single impulse is sent from the transmitting station. This special impulse is a negative impulse over main line conductors L^1 and L^2 simultaneously. The arrival of this impulse at the receiving station causes the energization of polarized relays 101, 102, 106, and of the neutral relays 104 and 108 which attract their armatures establishing a circuit which may be traced from battery 143, group relay 137, conductor 130, switching lever 114, conductor 125, front contact and armature of negatively polarized relay 101, conductor 126, front contact and armature 85 of neutral relay 108, to ground. The relay 137 is energized attracting its armatures and establishing a circuit which may be traced from battery 201, back contact and armature of selector relay 202, spacing magnet 100 209, resistance 243, front contact and top armature of group relay 137, conductor 234, armature and back contact of special relay 235, to ground. The spacing magnet will therefore be energized to move the carriage 105 a space to the left so that when during the printing operation of the subsequent character the spacing magnet is again operated, a clear space will be left between the two characters printed. This special single impulse 110 120 125 130

not only acts to control the spacing magnet but also acts as a readjusting impulse in certain cases of derangement of the apparatus. It may happen that in transmitting 5 impulses to print a word the first impulse of one letter thereof becomes lost. In this case the second impulse of a letter acts as the selecting impulse, the first impulse of the succeeding letter acting as the controlling 10 impulse to initiate the printing operation. Such a condition will obviously result in the selection of letters bearing no resemblance to the ones selected. When the end of the word is reached the spacing impulse is sent over 15 the line to operate the spacing magnet, acting at the same time as a "clearing out" impulse so that the combination of impulses for the first letter of the next succeeding word will operate in their proper order to 20 select the appropriate type magnet.

When the end of a printed line has been reached upon the paper, or when for any reason it is desired to start a fresh line thereon, a combination of impulses to operate the 25 paper lift and reset relay 41 is sent over the line from the transmitting station. The appropriate combination of impulses will select the relay 41 in precisely the same manner as hereinbefore described for the shift and back 30 shift magnets. This relay will therefore be energized and will close, first, a circuit from battery 244, through the contact plate 245 and the contact 246, which are in contact when the carriage is not in its initial 35 position, through the conductor 248, reset magnet 236, conductor 264, special relay 235, armature and contact of reset relay 42, conductor 249, armature and front contact of the relay 41 to ground; second, a locking circuit 40 for the relay 41 from battery 250, through contacts 251 and 252, conductor 253, lower winding, front contact and armature of relay 41 to ground. The first of the above circuits energizes the reset magnet and the 45 special relay. The reset magnet attracts its armature 254, removing the pawl 255 attached thereto from engagement with the pinion 256, fastened to the shaft 238, and the carriage is returned to its initial position by 50 power transmitted to the shaft 238 from the spring 257. At the same time it will be observed that the special relay 235 being energized has drawn its armature away from its 55 back contact making it impossible for the spacing magnet to be energized by current from battery 201 and thereby interfere with the proper return of the carriage to its initial position with a consequent derangement of the printed record or of the mechanism 60 itself. When the carriage 270 has reached its initial position the contact 245 will be moved out of engagement with the contact 246 and into engagement with contact 247. When this occurs the reset magnet and the 65 special relay will be deenergized but a cir-

suit will be closed from battery 244, through the paper lift magnet 258, conductor 259, the front contact and armature of the relay 41 to ground. The paper lift magnet being energized will attract its armature 260 and 70 through the medium of arms 261 and 262 raise the paper the proper distance for a new line of printed characters. At the same time the projection 263 on the armature 260 will move contact 252 away from contact 251, 75 thus opening the locking circuit for the relay 41 allowing its armature to return to normal position and also opening the energizing circuit of the paper lift magnet. The entire apparatus is now in normal condition with 80 the carriage in its initial position and the recording medium or paper elevated the proper distance for printing a new line.

If it is desired to reset the carriage without lifting the paper, it may be accomplished 85 by first energizing the reset relay 42 in a manner now well understood. Energization of relay 42 causes it to attract its armature establishing a circuit which may be traced from battery 244 through contacts 245 and 90 246, conductor 248, reset magnet 236, conductor 264, special relay 235, armature, front contact and lower winding of relay 42, to ground. The magnet 236 is therefore energized attracting its armature 254, thus 95 removing pawl 255 from engagement with the pinion 256, and the carriage is returned to its initial position by the spring 257. When the carriage reaches its initial position it breaks, at contacts 245 and 246, the energizing circuit above traced, allowing all parts of the apparatus to return to normal condition.

It will be observed that the circuit for the shift magnet 226 not only passes through the 105 front contact and armature of the shift relay 43 and the back contact and armature of the back shift relay 44, but also through the armature and back contact of the special relay 235. This arrangement is for the purpose of causing a deenergization of the shift magnet 226 and incidentally of the shift relay 43 each time a new line is begun. The object of this is that the shift magnet having been energized it might be maintained thus 110 either through inadvertence or through some sticking of the shift relay or the back shift relay, and therefore this means of deenergizing the shift magnet at the end of each line is provided in order that the shift magnet 115 120 may be deenergized and the type wheel 221 restored to its normal position automatically and without the knowledge of the operator at the beginning of each new line. In this way it is assured that each line will 125 begin correctly, even though the printed record of a part of the line preceding was confused and inaccurate for some reason.

While I have shown on the drawings a plurality of batteries or sources of current, it 130

will be understood that where such batteries or sources of current are of the same character or potential and located at the same place, they may be and preferably are one and the same battery or source of current.

What I claim is:—

1. In a selecting mechanism the combination of a plurality of selecting branches, a plurality of marginal selectable magnetically operated devices therein each having a plurality of fixed windings, and means for causing the operation of any device by energizing two windings thereof.

2. In a selecting mechanism the combination of a plurality of selecting branches, a plurality of selectable magnetically operated devices therein, each device having a plurality of fixed cumulative windings, and means for causing the operation of any device.

3. A plurality of magnetically operated devices each having a plurality of fixed actuating windings, means for connecting corresponding windings in series in groups, and means for causing the energization of a plurality of groups of windings whereby an electromagnetically operated device is actuated.

4. In a selecting mechanism the combination of a plurality of marginal selective magnetically operated devices, each having a plurality of cumulative windings, said windings being arranged in groups, and means for completing a circuit through a plurality of groups of windings in series to energize a plurality of windings of one device to cause the operation thereof.

5. In a printing telegraph the combination with a movable character carrier, of a selecting circuit composed of a series of branches including a character-determining branch and a printing magnet branch, a character selecting magnet having two windings in series in said character-determining branch, a printing controller magnet in said printing magnet branch, means for closing one branch through the windings of a character selecting magnet to position the character carrier, and means for operating the printing magnet branch.

6. In a telegraph receiver, a plurality of magnets from which one is to be selected, each magnet selected by a combination of but two impulses, a receiving mechanism responsive to impulses from a line, a selector for determining the magnet to be selected, and operated by the first impulse received by the receiving mechanism, switching members controlled by the selector, a circuit for said determined magnet closed through a switching member and said selector by the second impulse received by the receiving mechanism.

7. In a printing telegraph receiver, an operating circuit, a plurality of marginal

magnets each having two cumulative windings, said windings of each magnet being contained in different series sections of said circuit, a plurality of corresponding windings of a group of such magnets being in series in each said section, means for selecting one of said sections, means for subsequently selecting and closing another of said sections and thereby causing the selection of the said magnet having a winding in each of said sections.

8. In a telegraph receiver apparatus, an operating circuit, a plurality of type magnets, having marginal magnetic structures and each having a plurality of windings, each of the windings of each magnet being in a different section of said circuit, a series of group relays selectively operated by impulses received from a distant station, each adapted to close a section of said circuit through one of the windings of a desired type magnet, and a series of contacts one of which may be selectively closed to close a section through another winding of said desired type magnet and complete said operating circuit.

9. In a telegraph receiver apparatus, an operating circuit having a selecting branch divided into two sections, and a printing branch, a plurality of type magnets each having a plurality of cumulative windings and a marginal magnetic structure, each of the windings of each magnet being in a different section of the selecting branch, a series of group magnets selectively operated to close a section of said selecting branch of said circuit through one of the windings of a desired type magnet, and a series of contacts one of which may be selectively operated to close a section through another winding of said desired type magnet and complete said operating circuit, a character selected by said operating circuit, and a printing magnet in the printing branch operating to print the selected character.

10. An impulse receiving apparatus responsive to impulses received from a distant station, an operating circuit established by the receiving apparatus and having a plurality of branches, a plurality of type magnets having two windings, each being in a separate branch of the operating circuit, each being selectively energized by a combination of impulses received by the receiving apparatus, a series of group relays selectively operated by the first impulse of a combination of impulses and closing one of the branches of the operating circuit through one of the windings of the selected type magnet, a locking circuit for the selected group relay including a switching relay operating after the cessation of the first impulse of a combination of impulses, a switching lever operated thereby to close a second branch through the second winding

of the selected type magnet on the initiation 5 of the last impulse of the combination of impulses, a printing magnet in another branch of said operating circuit operating to print the selected character, a circuit-holding magnet in the first said branch of the operating circuit acting to hold the selected type magnet energized through one winding thereof after the cessation of the 10 last impulse of the combination of impulses, whereby the first impulse of a succeeding combination of impulses may selectively operate one of a series of group relays before the printing operation has taken place.

11. In a telegraph receiver apparatus, an operating circuit having a selecting branch divided into two sections, and a printing branch including a stop magnet and a printing magnet, a plurality of type magnets, 20 each having a plurality of windings, each of the windings of each magnet being in a different section of the selecting branch, a series of group relays selectively operated to close a section of said selecting branch of 25 said circuit through one of the windings of a desired type magnet, a series of contacts, one of which may be selectively operated to close a branch through another winding of said desired type magnet and complete said operating circuit, a movable character carrier 30 operated by said stop magnet and held in selected position by the desired type magnet, the printing magnet operating on its back stroke to print the character selected by the 35 desired type magnet.

12. In a telegraph receiver apparatus, an operating circuit having a selecting branch divided into two sections, and a printing branch including a stop magnet and a printing magnet, a plurality of type magnets each having a plurality of windings, each of the windings of each magnet being in a different section of the selecting branch, a series of group relays selectively operated to close 40 a section of said selecting branch of said circuit through one of the windings of a desired type magnet, a series of contacts, one of which may be selectively operated to close a branch through another winding of said 45 desired type magnet and complete said operating circuit, a circuit-holding magnet in a section of said selecting branch energized upon the completion of said operating circuit and locked in said energized condition 50 thereby, holding the desired type magnet energized through one winding after the de-energization of the group relay, a movable character carrier operated by said stop magnet and held in selected position by the desired type magnet, the printing magnet 55 operating on its back stroke to print the character selected by the desired type magnet.

13. In a printing telegraph, the combination 60 with a movable character carrier, of a selecting circuit composed of a series of

branches, including a character-positioning branch and a printing magnet branch; a printing controller magnet in said printing magnet branch; a main circuit; relays in said circuit responsive to succeeding pairs 70 of impulses in said main circuit to close said character-positioning branch and said printing magnet branch, respectively, a relay controlled thereby, and means controlled by said second mentioned relay whereby the operation 75 of determining a succeeding character may overlap the operations controlled by said printing controller magnet.

14. In a printing telegraph, the combination with a movable character carrier, of a selecting circuit composed of a series of branches, including a character-positioning branch and a printing magnet branch; a printing controller magnet in said printing magnet branch; a main circuit composed of 80 two independent conductors, relays in said circuit responsive to succeeding pairs of impulses in said main circuit to close said character-positioning branch and said printing magnet branch, respectively, a second relay 85 controlled by said main circuit relays, and means controlled thereby whereby the operation of determining a succeeding character 90 may overlap the performance of the operations under the control of said printing controller magnet.

15. In a printing telegraph, the combination with a movable character carrier, of a selecting circuit composed of a series of branches, including a character-positioning 100 branch and a printing magnet branch; a printing controller magnet in said printing magnet branch; a main circuit composed of two independent conductors, polarized relays in said circuit responsive to succeeding 105 pairs of impulses in said main circuit to close said character-positioning branch and said printing magnet branch, respectively, group relays controlled thereby, and means under the control of said group relays 110 whereby the operation of determining a succeeding character may overlap the performance of the operations controlled by said printing controller magnet.

16. In a printing telegraph the combination of a main circuit, relays in said circuit; a movable type carrier, a local selecting circuit controlled by said relays; said circuit having a character-determining branch, a two-coil magnet having both coils in said 115 branch, a group relay, a local circuit including the coil of said relay, and contact points operated by a main line relay; and a transfer switch having contact points in the group relay circuit, and means whereby the 120 cessation of the first impulse operates said transfer switch.

17. In a printing telegraph the combination of a main circuit, relays in said circuit at the receiving station, a movable type 130

carrier, a local selecting circuit controlled by said relays; said circuit having a character-determining branch, a two-coil magnet having both coils in said branch, a group 5 relay, a local circuit including the coils of said relay and contact points operated by a main line relay; a transfer switch having contact points in the group relay circuit, and means whereby the termination of the 10 first impulse operates the transfer switch, closes break points in said character-determining branch and locks said circuit closer.

18. In a printing telegraph the combination 15 of a main circuit, relays in said circuit at the receiving station, a movable type carrier, a local selecting circuit controlled by said relays; said circuit having a character-determining branch, a two-coil magnet 20 having both coils in said branch, a group relay, a local circuit including the coils of said relay and contact points operated by a main line relay; an electromagnetically operated transfer switch having contact 25 points in the group relay circuit, means whereby the termination of the first impulse operates said transfer switch; a printing magnet, and means whereby the second impulse operates said printing magnet.

19. In a selector for a printing telegraph, the combination of a series of two-coil type magnets, a series of branch circuits, each branch including both coils of one of said 30 magnets, a group relay, an electromagnetic transfer switch, a local circuit including the coil of said group relay and main line relay contact points, a branch circuit including the coil of said transfer switch, and contact points controlled by said group relay, and 35 means whereby the impulse in said main line relay at its cessation closes and locks said group relay and said transfer switch branch.

20. In a selector for a printing telegraph, 40 the combination of a series of two-coil type magnets, a series of branch circuits, each branch including both coils of one of said magnets, a group relay, an electromagnetic transfer switch, a main line relay, a local 45 circuit including the coil of said group relay and main line relay contact points, a branch circuit including the coil of said transfer switch, and contact points controlled by said group relay, means whereby 50 the impulse in said main line relay at its cessation closes and locks said group relay 55

and said transfer switch branch; a restoring relay and a circuit-holding magnet in the type magnet branch acting to restore the group relay to normal and to hold a circuit 60 through the type magnet respectively on a succeeding impulse from the line, whereby another succeeding impulse over the line may again operate the group relay before the operation of the selected type magnet. 65

21. An impulse receiving apparatus responsive to electrical impulses, a series selecting circuit established by the receiving apparatus, a plurality of type magnets having two energizing windings, each winding 70 being in a separate branch of said series circuit, said magnet being energized by a combination of impulses received by the receiving apparatus, a series of group magnets selectively operated by the first impulse of 75 a group of impulses and closing one of the branches of the series circuit through one of the windings of the selected type magnet, a locking circuit for the selected group relay including a switching relay, said switching 80 relay operating after the cessation of the first impulse of the combination of impulses, a switching lever operated thereby to close the second branch of the series circuit on the initiation of the second impulse 85 of the combination of impulses, a circuit including a printing magnet operating after the cessation of the second impulse of the combination of impulses to print the character selected by the type magnet and means 90 in the series selecting circuit whereby the first succeeding impulse of the combination of impulses may selectively operate the series of group magnets before the printing magnet has operated. 95

22. In a telegraph receiver, the combination with a movable character carrier, of a selecting circuit composed of character positioning branches and a printing magnet branch; a main circuit; means therein for 100 closing said character positioning branches and said printing magnet branch; and means whereby the operation of determining a succeeding character overlaps the operation of printing the preceding character. 105

In witness whereof, I hereunto subscribe my name this 21st day of November A. D., 1911.

CHARLES E. SCRIBNER.
